WINDOW JACK

Frank J. Cantrell, San Francisco, Calif., assignor
of forty-nine per cent to Eleanor Josephine
Koch, San Francisco, Calif.

Application February 28, 1945, Serial No. 580,183

4 Claims. (Cl. 304—24)

1

This invention relates to window jacks, and more particularly to a safety window seat especially useful in supporting persons engaged in washing, polishing or otherwise working on the exterior of windows in buildings.

Principal objects of this invention are to provide a seat which may be easily affixed to any given window in a manner insuring safety of the user thereof; to provide a seat which is compact in design, which may be quickly and efficiently transported from place to place and fixed in operative position with a minimum effort; and to provide a seat adapted to be used by window cleaners, or the like, which may be adjusted conveniently in accordance with the individual desire of the user after initial positioning and occupancy of the seat. A further object of the invention is to provide a window jack, having adjustable safety elements, obviating difficulty of attachment to various designs of window structure.

Further objects are to provide a window jack which is sturdy of construction and simple in design and which may be manufactured at low cost; and to provide a unitary window jack, wherein safety and comfort are combined without sacrificing simplicity of use and structure. Other objects and advantages will be apparent upon reference to the accompanying specification and drawing in which similar characters of reference represent corresponding parts in the several views.

Fig. 1 is a side elevation of my invention attached to a window of conventional construction.

Fig. 2 is a top plan view of my invention.

Fig. 3 is a bottom plan view of my invention with the sill support member partly broken away.

Fig. 4 is a fragmentary sectional view taken on line IV—IV of Fig. 2.

Referring to the drawing, the novel window seat is disclosed attached to a conventional window structure wherein A represents the interior moulding sill and B the exterior inclined sill or window ledge. C represents a conventional window frame vertically slidable in casement D.

A platform member is generally indicated at 10 and is provided with a back rest 11 which may be rigidly or integrally attached to the platform member or in any suitable manner. Horizontal base members 12 are rigidly affixed to the sides of the platform member 10 and extend forwardly thereof. Cross member 13 is rigidly attached to the forward ends of members 12 and is preferably formed to extend laterally a short distance be-

2

yond members 12 to form safety stop portions 14 adapted to abut against the inner wall of casement D when the seat is in operative position.

Vertical posts 15 are rigidly affixed to members 12 in front of the platform member 10 and are preferably formed so that they curve slightly away from the platform member to form camming surfaces, as at 16. A hook member 17 is 10 slidably carried under platform 10 and cross member 13, the hook portion 18 thereof being adapted to engage the interior moulding sill A. The shank of the hook member 17 is provided with longitudinal slots 20 and 21. Slot 20 is 15 provided with a threaded bolt 22 having a flat head which is slidable in said slot and adapted to project upwardly therethrough and through an aperture provided in cross member 13. Said bolt carries a wing-nut, or the like, 23. By tightening 20 nut 23 the hook member may be clamped in a fixed position relative to cross member 13. Hence by regulation of hook member 17 the platform member may be readily adjusted to form an effective safety hook for use with varying window 25 constructions.

It is noted that a guide stud 25, rigidly fixed to platform member 10, projects through slot 21 and acts as a guide for hook member 17 to prevent lateral movement thereof relative to said 30 platform member. It is also noted that a groove may be provided in cross member 13 to receive the shank portion of hook member 17. In the drawing, the slot has been omitted for clarity of illustration.

An axle 26 is pivotally mounted in bearings 27, provided on base members 12 and positioned below approximately the forward edge of platform member 10. Adjustable sill support 28 is rigidly or integrally fixed to said axle so that it 40 may swing vertically relative to base members 12 and platform member 10. The support 28 comprises a flat piece of metal or other suitable material having an aperture 29 provided therein at the rear and centrally thereof. In the drawing, 45 the support 28 is shown as generally triangular in form, but it is obvious that it may be rectangular or other shape.

A hole 30 is provided in platform member 10 near the rear thereof. A nut-forming member 31 is fixed on the underside of platform member 10 and is vertically spaced therefrom. A bolt 32 is threadably carried in said nut-forming member so that the knurled head 33 thereof is located below the platform member 10. Preferably the 50 nut-forming member 31 comprises a bracket fixed

by screws or bolts 34 to the underside of platform member 18 and provided with a threaded bore 35 positioned in vertical alignment with hole 30.

Bolt 32 is formed at one end with a double ball joint 36 adapted to engage support 28, through aperture 29, and whereby said bolt is rotatable with respect to said support. It is necessary that aperture 29 and bore 35 be in substantial vertical alignment with one another and positioned below hole 30. By turning the knurled head 33 of bolt 32 it is possible to elevate and lower the platform member relative to the building to which it is attached. The operator may have assumed his seat in the window jack and desire to elevate or lower himself relative to the window and may accomplish this purpose by simple manipulation of the bolt 32 by access thereto through hole 30.

From the above description it is clear that there are a number of safety and comfort features incorporated in the window jack, namely, an adjustable hook member 17 adapted to be positioned so that the hook portion thereof is fixed relative to the interior moulding sill of a window; a pair of vertical posts 15, adapted to be positioned adjacent to the interior face of window frame C, stop portions 14 adapted to abut against casement D; and bolt 32 adapted to regulate the vertical positioning of the device relative to the window after the operator has assumed his working position.

Although I have described the invention in more or less detail, it is understood that various modifications and variations may be practiced within the spirit of the invention and scope of the appended claims.

I claim:

1. In a window jack having a platform member and base members rigidly affixed thereto, a hook member slideable horizontally relative to said platform member, means to fix said hook member in rigid position, support means pivotally mounted on said base members and movable vertically relative thereto, and a unitary means to move said support means including a nut-forming member carried by said platform member, said last named unitary means positioned under said platform and in vertical alignment with an aperture formed therein whereby said means may be regulated by an operator after occupancy of said window jack

in order to raise or lower said platform without tilting said platform.

2. In a window jack having a platform member and base members rigidly affixed thereto, support means pivotally mounted on said base members and movable vertically relative thereto, a nut-forming member rigidly affixed to said platform member and vertically spaced from the underside thereof, a bolt threadably carried in said nut-forming member and rotatively engaged to said support member, and means provided in said platform member in vertical alignment with said bolt whereby ready access may be had to cause manual regulation of said bolt by an operator after occupancy of said window jack in order to raise or lower said platform without tilting said platform.

3. In a window jack having a platform member and base members rigidly affixed thereto, a pair of vertical stops adapted to abut against a relatively unmovable object, a hook member slideable horizontally relative to said platform member, means to lock said hook member in a fixed position, a sill support pivotally mounted to the underside of said base member, a nut-forming member rigidly affixed to the underside of said platform member and vertically spaced therefrom, a bolt threadably carried in said nut-forming means and rotatively engaged to said support member, and means formed in said platform member in vertical alignment with said bolt, whereby an operator may have ready access to said bolt for manual regulation thereof after occupancy of said window jack.

4. In a window jack having a platform member and base members affixed thereto, a hook member slideable horizontally relative to said platform member and adapted to engage a window sill, means to fix said hook member in rigid position, a support member pivotally and slidably mounted on said hook member, means to lock said support member to said hook member, a support means pivotally mounted on said base members and movable vertically relative thereto, unitary means to move said support means including a nut forming member carried by said platform member, and means formed in said platform in vertical alignment with said unitary means whereby an operator may have ready access to said unitary means for manual regulation thereof after occupancy of the said window jack.

FRANK J. CANTRELL.
